UNITED STATES PATENT OFFICE.

THOMAS J. NARDI, OF WORCESTER, MASSACHUSETTS.

MECHANICAL TOY.

SPECIFICATION forming part of Letters Patent No. 760,642, dated May 24, 1904.

Application filed January 2, 1903. Serial No. 137,478. (No model.)

To all whom it may concern:

Be it known that I, THOMAS J. NARDI, a citizen of the United States, and a resident of Worcester, in the county of Worcester and State of Massachusetts, have invented certain new and useful Improvements in Mechanical Toys, of which the following is a specification.

My invention relates to mechanical toys; and it consists in the improved construction and arrangement of parts hereinafter described, and pointed out in the appended claims.

The invention is susceptible of various embodiments and will be specifically described in connection with the accompanying drawings, which illustrate the device embodying a novel arrangement for causing the movement of a part of a toy figure—for instance, the leg—by means of a weight.

In the drawings, Figure 1 is a front elevation of a toy embodying the invention. Fig. 2 is a vertical sectional view of the construction disclosed in Fig. 1, the section being taken in the plane indicated by the broken line 2—2.

Within the casing is a weight 2 of general triangular shape, having a rounded side 3 and a lower side 4. From the vertical side 5 of the weight projects a lug 6, which enters one end of a closely-coiled spring 7, the opposite end of the said spring being secured in any suitable manner to the adjacent peripheral portion of the casing. To the outer side of the front of the casing is pivotally secured a part 8 of a toy figure, (in this instance a leg,) and

the remainder of the figure is painted on the surface of the casing. From the upper end of the leg 8 projects a pin 9, adapted to be struck by the beveled underside of the weight. As shown by dotted lines in Fig. 1, two human figures are delineated upon the outer face of the casing, one in a stooping position and the other, of which the movable leg is a part, in a kicking attitude, the vibration of the leg through the medium of the weight giving the amusing result of the rear figure kicking the forward one.

By employing a circular casing the toy may be rolled along the floor or other suitable surface, with the result that the weight will vibrate between its extremes and cause a repe-

tion of the amusing effect occasioned by the movement of the pivoted external member each time the figures' delineations are brought into a position wherein the ludicrous representation can be appreciated.

It will be seen that the diameter of the coiled spring is such that the thickness of the weight 2 to provide a lug 6 for entering the end of the spring will be such that the front and rear sides of said weight lie closely parallel to the front and rear walls of the casing. This is obviously similarly true of both the lug and the spring. The advantage of these features are that the parts are positively guided in their movements and any tendency of such parts to bind is greatly reduced.

It will be understood that the invention is not restricted to the specific construction shown in the drawings, as the same is equally adapted for the movement of arms or any other part of either animal or human toy figures, and I therefore reserve the right to make all such variations or modifications of the device as may fall within the terms and scope of the invention.

I claim—

1. A mechanical toy, comprising a casing having a portion of a toy figure delineated on its outer surface, a pivoted part or element so attached to the casing as to form a part of the figure, and having a pin projecting therefrom, and a movable spring-controlled weight adapted to strike said pin to vibrate the pivoted part or element.

2. The combination with a hollow casing, of a weight supported therein, a spring attached at one end to the weight and at its opposite end to the casing, a device pivotally secured to the outer face of the casing and forming a part of a toy figure, and a pin projecting therefrom to be struck by the under side of the weight.

Signed at Worcester, in the county of Worcester and State of Massachusetts, this 18th day of December, A. D. 1902.

THOMAS J. NARDI.
